CALIFORNIA.

FLANGE AND RAIL LUBRICATOR.

1,211,424.

Specification of Letters Patent.

Patented Jan. 9, 1917.

Application filed March 10, 1915. Serial No. 13,534.

To all whom it may concern:

Be it known that we, CARL HENRY EPPLE and GEORGE A. WHITE, citizens of the United States, residing at Oakland, in the county of Alameda, and Red Bluff, in the county of Tehama, respectively, and State of California, have invented certain new and useful Improvements in Flange and Rail Lubricators, of which the following is a specification.

This invention relates to flange and rail lubricators and more particularly to means for lubricating the rails on track curves.

The principal object of our invention is to provide means for automatically supplying a given amount of lubricant on the inner face of the rail head each time a car wheel passes this point.

Another object of our invention is to so arrange the system that the lubricant is provided at the beginning of the curve in relation to the passage of the train, and where the train passes in the opposite direction the lubricant would be provided at the other end of the curve.

With these and other objects in view our invention consists in the novel construction, combination and arrangement of parts as herein described and more particularly pointed out in the appended claims.

Reference being had to the accompanying drawing forming a part of this specification, Figure 1 is a view in plan of a portion of railroad track showing two of our lubricating devices located at each end of the curve. Fig. 2 is an enlarged transverse section through one of the oil reservoirs and the valve used in connection therewith. Fig. 3 is a transverse view in section through the rail showing the contact making device attached thereto. Fig. 4 is a diagrammatic view of the circuit employed in connection with the lubricator. Fig. 5 is a view in transverse section through the lubricant reservoir. Fig. 6 is an enlarged view of the head portion of the relay shown in Fig. 4.

Referring to corresponding parts by the same numerals of reference, 1 and 2 denote respectively, the outer and inner rail of the track curve. The inner rail being connected by conductor 3 to a source of electrical energy 4. The outer rail is divided in two sections, 1^a and 1^b by the insulating joints 5, one of these joints being located at each end

of the curve and one approximately at the center thereof.

Our oiling device is denoted in general by 6 and we prefer to locate one of these adjacent each end of the curve, and slightly ahead of each oiling device is a contact maker, denoted in general by 7. The device 6 consists of a base 8 adapted to be clamped on the rail in any preferred manner and attached to this base or formed integral therewith is a reservoir 9, this reservoir being provided within a removable top 10, which may be clamped down so as to form an air tight joint. Upon the rear of the reservoir is bolted a valve casing 11 having a passageway 12 extending into the reservoir and there connected to a pipe 13, the said pipe extending across the reservoir and having the exit passage opposite the inner face of the rail head 15. Within the reservoir, the pipe is provided intermediate its length with a fitting 16 having a side branch 17 to which is screwed a pipe 18 extending downwardly to a point adjacent the bottom of the reservoir. In the other end of this side branch 17 is screwed a pipe 19, which is concentric with the pipe 13 and extends to the outer end of this pipe. The passageway 12 is provided with a side branch 20, which opens into the top of the reservoir, as shown in Fig. 5.

On one side of the reservoir is provided a filling tube 21 closed by the cap 22, or other preferred means, the top of this filling tube being below the opening 20 so as to eliminate any chance of the oil surface reaching this opening and flowing into the passageway 12. The passageway 12 is provided with a valve seat 25 whereon is seated the disk 26, the latter being fastened to the stem 27 extending through the packing gland 28 having on its outer end the solenoid core 29.

30 denotes a solenoid, one terminal of which is grounded on the rail, the other terminal being connected by conductor 31 with the contact device 7. This latter consists of a curved strip 31' adapted to rest against the rail and be held thereto by means of the spring 32. The strip 31' has an arm which is attached to the shaft 33, this shaft being pivotally mounted in a bearing in plate 34 by which the device is attached to the rail. To one side of this arm is attached a casing 35 within which a second arm 36 is attached

to the shaft 33, the outer end of this arm carrying contact screw 38 to which conductor 31 is connected and which is adapted to make contact with the spring 39, the latter being connected by conductor 40 to the relay 41. This relay consists of two coils 42 and 43 connected by conductors 44 and 45 with the rail section 1—a and 1—b respectively. The coils act on the armatures 46 and 47, the ends of which are adapted to contact with the faces 48 of the head 49. When this contact takes place the head is bent to one side and the spring supporting member 50 makes contact either with 51 or 52, depending in which direction the head is moved.

The upper end of the head is provided with a projection 53, which is adapted to be caught by the catches 54 on the ends of the armatures 46 and 47. The contact 51 is connected by conductor 55 with the contact device 7 on the end of the curve opposite rail section 1—a, while the other contact 52 is connected by conductor 56 with the contact device adjacent the rail section 1—b. The central spring 50 is connected by conductor 57 with one side of the course of current 4, which same side is connected by conductors 58 and 59 to the relay coils 42 and 43.

The operation of this device is as follows:—When the forward trucks of a train enter the curve, say, on the left hand of Fig. 4, a circuit is established between the rail 2 and the section 1a. This causes current to flow from battery 4 over conductor 3, rail 2, through the wheels and axles to section 1a, over conductor 45 to relay 43 to conductor 59 back to battery. This pulls down armature 47 and moves the head 49 so that the center spring 50 makes contact with 51, which causes the circuit from battery to flow over conductor 57 through these springs, conductor 55 to spring 39 of device 7 adjacent 6a. The conducting screw 38 is connected by conductor 31 to the solenoid 30 of the ciling device 6a, thence over rail 2 back to battery 4. Thus this circuit is complete except the closing of the gap between spring 39 and contact 38, which takes place each time the wheel passes between the rail 2 and plate 31. When this takes place the solenoid 30 is energized lifting the valve 26 from its seat allowing air to flow from pipe 60 through the passageway 12, pipe 13 to the exit opening. A portion of the air also flows through the branch 20 into the interior of the reservoir above the oil. This pressure tends to force oil upward through the pipe 18, the fitting 16, and out the short pipe 19, which tendency together with the atomizing action of the air passing out the end of the pipe 18, sprays a small quantity of oil from the end of pipe 19 against the face of the rail head 15. This action takes place each time the wheel passes the contact device 7 furnishing a constant supply of lubricant

to the rail while train is passing around the curve. If the curve is very long or sharp several of these devices may be provided at intervals. The pipe 60 is provided with air from the storage reservoir 61, which is kept at substantially constant pressure in any preferred manner. When a train enters the section of track denoted by 1^b, the circuit is completed to the relay coil 42 pulling down the armature 46, which owing to the head being displaced by the armature 47, causes the catch 54 of armature 46 to engage 53 so that while the contact device of this section operated to complete the circuit between the spring 39 and screw 38 no oil is sprayed by the device 6^b owing to the circuit being open between 50 and 52.

When the rear of the train leaves the section denoted by 1—a, the armature 47 is restored to its normal position, but the armature 46 still holds the head to one side and still prevents the contact between the spring 50 and 52, so that while the rear part of the train is passing the second half of the curve no oil is sprayed.

It will thus be seen that we have provided for automatically and continuously lubricating the inner face of a rail head while the train is passing around the same. The device operating to lubricate the rail at the beginning of the curve is arranged to operate on single as well as double track systems, on the latter it being necessary to employ the relay 41, the contact device being directly connected to complete the circuit from the source of current to the solenoid 30.

While we have shown the preferred embodiment of our invention it will be understood that minor changes in detail of structure may be resorted to within the scope of the claims.

What we claim as new and wish to cover by Letters Patent is:—

1. In combination with track rails, an oil reservoir, and means initiated by the passage of a wheel flange for spraying a quantity of oil against the side of the rail head from said reservoir.

2. In combination with track rails, an oil reservoir, an electrical contact maker operated by the train wheel passing over said track rails, a spray nozzle connected with said oil reservoir, a valve for admitting air under pressure to said spray nozzle, electrical means for operating said valve, and an electrical circuit connecting said valve operating means with said contact maker.

3. In combination with the track rails of a curve, of oil spraying mechanisms located adjacent each end of said curve, contact makers located at each end of said curve adapted to be moved by the passage of the train wheel flanges to operate said oil spray mechanism, a relay adapted to electrically con-

nect the spraying mechanisms and the contact maker at the end of the track curve where a train enters, and to prevent an electrical connection between the spraying mechanisms and contact maker adjacent the exit end of the curve during the passage of the train through the said curve.

4. In combination with track rails, an oil reservoir, an electrical contact maker operated by the passage of a train wheel flange along said track rails, a spray nozzle at-

tached to said reservoir, electrical means for causing the operation of said spray nozzle and an electrical circuit connecting said contact maker with said electrical means. 15

In testimony whereof we affix our signatures in presence of two witnesses.

CARL HENRY EPPLE.
GEORGE A. WHITE.
